(54) **WARMING ROOMS, & MANAGEMENT OF
HEAT**

(76) Inventor: **Robert B. Varden**

Robert B. Barden.
Patent

The schedule refers to the above Letters Patent and making part of the same containing a description in the words of the said Robert B. Barden himself of his improvement in the management of heat for warming rooms called "The Fuel Saver or Economical House Warmer."

Be it known that Robert B. Barden of Baltimore in the County of Baltimore and State of Maryland have made a new and useful improvement in the management of heat for warming rooms called "The Fuel Saver or Economical House Warmer" which is described as follows —

The chimney is constructed by raising four walls of brick stone or cast iron or both in a proper foundation leaving suitable openings for the fire place, floor, air chamber, out lets and inlets for cylinders pipes and other necessary appendages hereafter described. The fire place of the first story is made of cast iron in one piece and set into the brick work of the chimney on each side and over the top in front and resting on the hearth is placed a metallic frame containing cold air admitted from the cellar or elsewhere through apertures in the hearth to create a draft in the fire place the air having access to the fire place through small apertures in the sides of the metallic hollow frame. In the centre of the hearth is another passage for the admission of cold air from the cellar or elsewhere to the fire place. This passage is covered by a metallic base having small apertures through its top and sides of the fire to admit the air to the fire. An air chamber is constructed behind the cast iron fire place covered at top by a iron plate cutting off the smoke from it. The air in said chamber being heated by the sides & back of the fire place and by the passage of the smoke & flame over the plate just mentioned the heated air is admitted into the room from said chamber through openings on the sides thereof. A cylinder to contain heated air is placed above the iron plate of the air chamber and opens except the chimney it contains many iron fittings made in the side plates of plates to receive them, etc.

placed in such a manner as to allow of free draft around it, and around it is a ventilator to permit a free passage of heated air into the room, or to shut it off; in the chimney is a door to admit articles to be heated if necessary, which are to be placed on a false bottom in the cylinder or oven, on the top of the cylinder are two pipes opened or closed when required by dampers on the ends of rods extending through the side walls or plates of the chimney. One of these pipes is smaller than the other, the larger one conducts the heated air from the cylinder to another chamber for heated air hereafter to be described, the smaller one when uncovered allows all impure air in the cylinder to escape into the flue. There are also two pipes on the outside against the back of the chimney, one end of each extending below the lower iron plate, and the other extending above the upper plate or each placed over the cylinder these pipes carry the heated air from the lower to the upper heated air chamber. A scoop is placed between the cylinder and iron plate over the lower heated air chamber to remove the soot which may collect on the top of said plate. The upper heated air chamber is formed by the upper part of the second story, hearth, the walls or plates of the chimney and the arch or plate over the cylinder and the iron floor hereafter described. Through the hearth of the second story and communicating with the upper heated air chamber are two passages for the admission of the heated air from said chamber into the rooms of the second story, there are also two round openings through said hearth into which are inserted brick or other tubes or pipes to convey the heated air to the third story or whatever stories. At front of the fire is made of iron commencing at the lower part of the arch or plate against the back wall of the chimney and after passing through the upper heated air chamber heats the air there and extends a sufficient distance when the brick work of the floor commences and is continued through the roof, at a suitable distance from the chimed hearth there is an opening made on the front of the chimney, and the opening at the bottom there is a bar of iron to which is hinged a door or shutter of sufficient weight to close the opening when required.

for small bars to be attached to it may be with a screw or pinned at pleasure. Into the opening may be inserted the pipe of a flue of a size by which the second story of the house may be warmed when there is no need of fire in the first story. The Second Warmer or Economical Warmer. In the third story (or in any other story in which the warmer hereafter to be described is to be used) is made an opening on the wall of the chimney, about the size of the flue of the chimney, so that this opening at the top is secured a bar of iron to which is hinged a swinging valve operated by a rod or bar of iron in front, to cut off the passage of the smoke up the flue and turn it horizontally through the opening just mentioned into the said second or economical warmer through an opening in the back, near the bottom thereof. This warmer is of a round, square or other shape made of rolled, wrought or cast metal about 5 feet high & feet long, and 18 feet wide closed entirely except where the smoke is admitted and escapes and where the air cylinders are situated and a small opening in front for the rod or bar above mentioned. The air cylinders are three in number but may be more or less, placed longitudinally at a proper distance apart and within the warmer open at both ends, to allow of a free passage of the heated air from them on to the room; in the top is another opening, the size of the flue as usual which is formed a flange or projection over which is placed a square pipe or conductor the same size as the one last mentioned, to carry the smoke after its having entered the warmer & circulated around the several air cylinders through an opening in the chimney against the flue. The pipe or conductor intended to carry the smoke from the warmer to the flue has the other end thereof placed in the last mentioned opening in the chimney. Besides the pipe or conductor last mentioned there is another one of the same size to be made of rolled or wrought or cast metal or of clay burnt in one - burnt to be used in conducting the heat from the chimney to the warmer. Besides the valve before described for changing the direction of the smoke from the flue to the warmer, three others may be used, the first is hinged at the end of the conducting pipe, the second is placed within the pipe, both move to close the flue of the chimney to prevent the smoke

they are attached, extending through the front of the furnace, the tube is simply a plate of metal passing horizontally across the face of the chimney, varying where between the two conducting pipes of the furnace. A dump-
er is also placed in each of the conducting pipes. On the front of the furnace
is an opening to admit a stone pipe from a stove to be used where
there is no fire in the first story. The exhaust and plates in the chimney
may be dispensed with and the air flow brought down to the front
of the fire place on the first floor. What I claim as my invention is the im-
provement and for which I took out a Patent of the before described
mode of removing heat by which a more accurate and cooking
performance from the caloric that usually escapes with the smoke through
the face of the chimney.
